IGNITION BOOSTER

Frederick William Claybrook, Cumberland, Md.

Application December 7, 1932, Serial No. 646,205

7 Claims. (Cl. 123—148)

The invention relates to improvements in the ignition systems of internal combustion engines and comprises a leak correcting assembly herein described which is either inserted in the high tension ignition line between the induction coil and the distributor, or is built into the induction coil as a part thereof.

The objects of the improvement are as follows:

1. To keep the potential off of the spark plugs until the potential of the induction coil has reached a value sufficient to produce a proper spark in the combustion chamber of the engine;
2. To prevent excessive leakage of current over and through the high tension ignition system;
3. To intensify appreciably the high frequency current in the high tension ignition circuit;
4. To provide an ignition booster or intensifier which may either be connected in the line of high tension ignition between the induction coil and distributor or may be built into the ignition coil;
5. To provide a booster which is simple, yet novel and efficient for the above mentioned purposes; and
6. To provide a booster which is so substantial in construction that it will not be injuriously affected by burning when employed for the purposes intended, or be subject to deterioration through corrosion, and in which the predetermined resistance of the device remains uniform under the strain of continued use.

Spark intensifiers have heretofore been connected either on each spark-plug of the engine, or in the conductor wire leading from the induction coil to the distributor; but the present invention is so designed that it may be connected either between the induction coil and the distributor, or be built into the induction coil as a part thereof.

Furthermore, spark intensifiers of auxiliary gap construction are frequently introduced in the ignition systems of internal combustion engines, but by nature of their construction the electrodes forming the gap are subject to more or less deterioration caused by burning away of the points. This very obviously increases the resistance in the high tension circuit until the efficiency of the device is sooner or later destroyed, thus creating liability of injury to the induction coil by causing it to overheat and break down under the too great load thereby increasingly imposed upon it. The present invention has been so designed as to overcome this objectionable feature of the spark intensifiers above described.

With the above and other objects in view, the invention further includes certain novel features and details of construction, to be hereinafter fully described, illustrated in the accompanying drawing and pointed out in the appended claims.

In the drawing:—

Figure 1 is a perspective view illustrating the invention connected in the distributor of an internal combustion engine.

Figure 2 is a similar view of the device removed from the cylinder casing or container.

Figure 3 is an enlarged vertical sectional view.

Figure 3a is a cross section of the tubular part 12 of Fig. 3.

Figure 4 is a perspective view showing the device mounted in an ignition coil as a part of the same.

Referring to the drawing, *b* indicates the casing or container, which may be made of hard rubber or any other suitable insulating material.

The opposite ends of the cylindrical casing *b* are provided with threads internally into which are screwed contact ends 2 and 2' of brass or other suitable conducting material. Contact end 2 is provided with a socket 3 of standard 20 diameter and depth to permit the snug insertion of the high tension lead wire 4 from the induction coil of an internal combustion engine. Contact end 2' is provided with a machine screw 10 which is longitudinally inserted through it to 25 engage a binding hex nut 11 and this screw projects far enough beyond the hex nut to permit an expansion tube 12 of brass or suitable conducting material to be screwed upon the same in rigid contact with hex nut 11. The expansion 30 tube 12 is for the purpose of connecting the device into the top of a distributor of an internal combustion engine. To serve that purpose it is longitudinally slotted at 13 through both sides and nearly its full length to permit sufficient 35 expansion and contraction to cause it to be snugly inserted in distributor caps having sockets of variable sizes.

The construction of the ignition boosting unit of the invention is as follows:

A metallic core 4 having a contact flanged head is passed through an insulating washer 5 of fibre or other suitable material, said washer being of slightly smaller diameter than the interior of the casing container *b*. A pile of very 45 thin mica washers 9, 9 are pressed closely together upon said metallic core 4 together with a washer 6 of fibre or other suitable insulating material, all of these being riveted upon the metallic core 4. The washers 9, 9 and washer 6 are all of the same 50 diameter on the outside as well as on the inside, but the outside diameter of same is sufficiently less than the inside diameter of the casing container *b* to form with the inner surface of container *b* an annular air cooling space *a*.

A ribbon conductor lead 8 of spring brass or other suitable material is bent in the form of a U spring one side of which parallels and engages in rigid contact the pile of mica washers 9, 9 on one side thereof. This spring conductor 8 60

is kept in place by being clamped at one end between the pile of mica washers 9, 9 and an insulating cap of porcelain 7 or other suitable material which covers the end of the metallic core 4 and the mica pile 9, 9, and is further held in rigid contact with the pile of mica washers 9, 9 by its pressure upon the inside of the casing container b. The ribbon conductor lead 8 is then carried beyond the end of the insulating cap 7 and bent into such shape as to make connection with contact end 2', while at the same time it serves to press the booster unit towards contact end 2 and keeps it in connection with same at the flanged contact head of the metallic core 4.

15 The operation of the invention is as follows: In the ignition systems of internal combustion engines, the leads, or conducting means from the spark-plug gaps, have a specified capacitance. If, however, there is a leak in the high tension line between the induction coil and the spark-plug gaps the maximum voltage will not be reached and, consequently, the spark will be diminished or it may not occur at all. This, of course, will depend upon the size or extent of 25 the leak.

Leads which have poor or worn insulation, imperfect connections, carbon in spark-plugs, or moisture on porcelains (which condenses while the engine is idle, especially at night or in cold 30 weather), all are to be regarded as leaks.

If, however, some practical means can be found to bring a portion of the high tension ignition circuit which has no leaks to a high potential, or sufficiently high voltage, and then, if by some 35 means this high potential portion of the circuit be connected in the line to the spark-plugs, the low potential portion of the circuit, i. e., the portion where the leaks exist, may be brought quickly to a potential sufficiently high to produce a spark 40 of the proper ignition value.

While the high tension ignition circuit still has the same leaks in it as before, yet the infinitesimal time required for the potential or voltage to build up proper strength in the low potential portion of the circuit is so much less 45 that a smaller charge of electricity passes through the latter; therefore, the potential of the entire circuit will be higher, and unless the leak or leaks prove too great for such a remedy—a short 50 circuit, for instance—the current will have a sufficient potential to fire regularly and efficiently at the spark-plug portion.

The invention herein described provides sufficient resistance to the current at low voltage 55 to allow the potential to build up strength on the induction side of the circuit. This invention operates upon the principle of a high resistance brush discharge condenser.

Referring to Figs. 3 and 4, the operation of 60 the invention may be readily followed. The current from the secondary winding 14 of the induction coil of an internal combustion engine enters the device from the induction coil socket 15 through the induction coil lead wire 1 which is 65 inserted in socket 3. It then passes through the metallic core 4 in a longitudinal direction until it meets an obstruction at the insulating cap 7 through which it cannot pass, whereupon it backs up and changes its course from a longitudinal direction to horizontal and then passes between 70 the mica washers 9, 9, to the ribbon spring lead conductor 8, whence it continues to the distributor, spark-plugs, and ground by the channel of the electrode contact 2', 10 and 12. The re-

sult is a rush discharge possessing higher potential and higher frequency value.

When the potential induced by the induction coil becomes sufficiently high the resistance of the device will immediately break down and allow 5 the current of high potential to pass. In other words, the described device has an infinite resistance until it is once overcome by the energy it condenses, when it becomes a very efficient conductor and allows the charge of high potential 10 to rush without interruption to the spark-plugs.

After the high potential charge has passed through the device, however, the resistance again becomes high until the induction coil has built up a potential strong enough to overcome it and 15 produce another spark of the proper ignition value across the gap of a spark-plug. Thus its operation as described above will be constantly repeated. The device therefore acts as an automatic switch which allows the high tension ignition current of an internal combustion engine to pass from the induction coil when the potential of the current is at its maximum capacitance and which seals the ignition system against 20 leaks while the induction coil is building up a 25 high tension or high pressure for the next spark.

The invention is susceptible of various changes in its form, proportions and details of construction within the scope of the appended claims.

Having described the invention what is claimed 30 is:—

1. An ignition intensifying device comprising a pile of thin washers composed entirely of refractory insulating material in facial contact with each other and centrally perforated, a conducting terminal extending through said perforations, and another conducting terminal in contact with the peripheries of said washers.

2. An ignition intensifying device comprising a pile of thin washers composed entirely of refractory insulating material in facial contact with one another and centrally perforated, a conducting terminal in contact with said washers at their inner edges, another terminal in contact therewith at their outer edges, and means for connecting said device in the spark-plug circuit of 45 an internal combustion engine.

3. In an ignition booster, comprising a metallic core having a flanged contact head, a pile of insulating washers closely pressed together and 50 firmly held in place on said metallic core, and a cap of refractory substance which completely insulates one end of said metallic core.

4. An ignition booster comprising a pile of thin washers of refractory material having a relatively 55 high resistance, a suitable container for said washers having members for connecting the same in the circuit of the induction coil, and contact terminals in said circuit, one making contact with the internal edges of said washers and the 60 other with the external edges thereof.

5. An ignition booster as specified in claim 4, wherein one of said contact terminals is a spring which exerts pressure endwise of said pile of washers.

6. An ignition booster, as specified in claim 4, 65 in which one of said contact terminals is a spring which exerts pressure laterally against said pile of washers.

7. An ignition booster, as specified in claim 4, 70 in which said washers are made of thin mica sheets.

FREDERICK WILLIAM CLAYBROOK.
